(57) **CLAIM**

The ornamental design for a shotgun shell holder, as shown and described.

DESCRIPTION

FIG. 1 is a front, left side, and top perspective view of a shotgun shell holder showing my new design. Individual shotgun shells and a box of shotgun shells are shown in broken lines and are not part of the design;

FIG. 2 is a top plan view thereof;

FIG. 3 is a front elevation view thereof;

FIG. 4 is a right side elevation view thereof;

FIG. 5 is a bottom plan view thereof; and,

FIG. 6 is a rear elevation view thereof.
